ABSTRACT: A control element for hydraulic cylinders particularly adapted for actuating working tools mounted on earth-moving machines and the like, wherein the front end of the control element is hydraulically biased against the force of springs to maintain the control element in a neutral position. In order to limit the stroke of the ends of the control element, pistons are provided at the ends which have a diameter larger than a diameter of the ends of the control element, and are displaced longitudinally between a pair of limits within variable springs. The springs are also supported between the inner side of the pistons and supports and caps, loosely placed over the ends of the control element. The caps serve as a collar or strap so that the ends are longitudinally displaced with respect to the control element housing.

CONTROL ELEMENT FOR HYDRAULIC CYLINDERS

This invention relates to a control element for hydraulic cylinders.

More specifically, this invention relates to a control element for actuating work tools mounted on earth moving machines like dredger shovels, etc., whereby the front ends of the control element are hydraulically biased against a spring force which retains the control element in a neutral position. The hydraulic bias for displacing the control element is precontrolled by a pilot member to facilitate manual switching.

Conventional control elements of the above-mentioned type could only be adjusted to one switching position on either side of the neutral position. In the present invention, the switching position of the control element is enlarged to an additional switching position on either side of the neutral position, in order to increase the switching range, a feature which in many cases is desirable. Pistons are provided to limit the stroke of the front ends of the control element between front end limits. The pistons have a larger diameter than the control element, and are displaced longitudinally between a plurality of abutments within respective variable cylinders. A spring is mounted between the inner side of each piston and its support. Open caps are loosely placed over the front ends of the control element. Instead of caps, straps, collars or the like, may also be used. The front ends of the control element are displaceable along a longitudinal direction with respect to the control element.

In accordance with the invention, only the outer ends of the pistons are fed with hydraulic fluid if the control element is maintained in a neutral position, a position which is exclusively affected by the springs. The springs press the support shoulders of the caps which are placed over the front ends of the control element, against the front faces of the control element housing. The caps thus maintain the front ends of the control element in a fixed position. In this position, one of the pistons engages its inner abutment and also provides the outer support for the spring. This position serves also as the first switching position where only one end of the control element is fed by hydraulic fluid. The front face of the control element is thus displaced to the opposite front face, since the piston remains in a fixed position at its inner abutments due to its larger diameter with respect to the control element. The second switching position, which is in the same direction, is affected since the outer front end of the opposite piston is relieved from the hydraulic fluid pressure, so that the piston is displaced from the inner abutments against the outer abutments. In the first, as well as the second switching position, the piston while being displaced as described, also moves its associated cap, spring, and the front end of the control element. The opposite front end of the control element is displaced longitudinally with respect to its stalled cap. The same switching movement takes place on the other side of the neutral position.

It is, therefore, an object according to the present invention to provide a control element for hydraulic cylinders which includes an additional switching position on either side of its neutral position in order to increase its switching range.

It is another object according to the present invention to provide a control element for hydraulic cylinders which is simple in design, inexpensive to manufacture, and reliable in operation.

Other objects and features of the present invention will become apparent from the following detailed description considered in connection with the accompanying drawings which disclose one embodiment of the invention. It is to be understood, however, that the drawings are designed for the purpose of illustration only and not as a definition of the limits of the invention.

In the drawings, wherein similar reference characters denote similar elements throughout the several views:

FIG. 1 shows the neutral position of the control element;

FIG. 2 shows the first switching position of the control element; and

FIG. 3 shows the second switching position of the control element.

Referring to FIG. 1-3, a control element 1 is mounted in housing 2 to control certain main and branch feeder lines *a*, *b*, *c*, *d*, *e*, *f*, *g*, and *h*, which for the purpose of subject invention are only of general interest. Control element 1 is precontrolled by a pilot member 3 which receives hydraulic fluid under pressure through feeder line 4 at input connection 5. A precontrol element 6 for pilot member 3 may be adjusted by handle 7 from a neutral or zero position into two switching positions I and II on one side of the zero position, and to two switching positions III and IV, on the other side of the zero position.

The extreme ends 1' of control element 1 are arranged as plunger pistons in variable cylinders 8. Caps 9, which are provided with openings 9, are positioned on top of ends 1'. Collars, straps, and the like, may be also used. Springs 10 press bearing shoulders 9" of caps against the outer front walls of valve housing 2 and engage the underside of pistons 11. Pistons 11 are displaceable longitudinally in variable cylinders 8, between inner abutments 12 and outer abutments 13. It should be noted that pistons 11 have a larger diameter than front ends 1' of control element 1. As can be seen in FIG. 1, in the zero position, pistons 11 are fed by hydraulic fluid under pressure, on their outer front face and are therefore held in a fixed position against inner abutments 12.

The inner bottom sides of caps 9 retain control element 1 in a fixed position on its outer front faces, since the plunger spaces of front ends 9' are not fed by hydraulic fluid under pressure.

In the first switching position I as shown in FIG. 2, the upper plunger space is fed by hydraulic fluid under pressure through line 15, while the hydraulic pressure can escape from the lower plunger space through line 16. Everything else, however, remains as shown in FIG. 1. Accordingly, the upper front end 1' of control element 1, is moved downward until its lower front face, together with its associated cap and spring, engage the inner side or wall of lower piston 11. This piston stays in its position at the inner abutment, because its diameter is larger than the diameter of the front end 1' of control element 1. The front end 1' is thus displaced longitudinally with respect to its stalled cap 9.

In the second switching position II, as shown in FIG. 3, the outer side of the lower piston within the variable cylinder 8 is relieved of hydraulic fluid under pressure by line 17. Lower piston 11 is therefore displaced with the same hydraulic pressure feed as described with respect to FIG. 2, and engages its outer abutment 13, together with its associated cap, spring, and also the lower face of front end 1'. The upper front end 1' is displaced a little further with respect to its stalled cap. The caps are sufficiently long so as to extend over both switching positions. The description for switching positions I and II are analogous for switching positions III and IV, having the same type of function and operation.

While only a single embodiment of the present invention has been shown and described, it will be obvious that many changes and modifications may be made thereunto without departing from the spirit and scope of the invention.

What is claimed is:

1. A control apparatus for hydraulic cylinders operated by a hydraulic fluid under pressure comprising:
an elongated hollow control element housing having
a cylinder on each end,
an elongated control element slidably disposed within said
housing, said cylinders including fluid-receiving apertures
communicative with the ends of said control element,
a piston disposed in each cylinder of said housing,
an open cap disposed over each end of said control element
within said cylinders,
spring means for spring biasing said caps with respect to said
pistons, said control element having a neutral position
when hydraulic fluid is fed under pressure through said
apertures to the top of each of said pistons in said cylinders,

- a first position when hydraulic fluid is additionally fed to one of said caps while being withdrawn from the other of said caps, and
  - a second position when hydraulic fluid is additionally removed from the top of said piston adjacent to the cap having the withdrawn fluid.
2. The control apparatus as recited in claim 1, wherein said caps include apertures communicative between the ends of

said control element and said pistons, said caps further comprising external flanges for supporting said spring means against the bottom surfaces of said pistons in said cylinders.

3. The control apparatus as recited in claim 2, wherein each of said cylinders further comprise an abutment for limiting the movement of said piston with respect to said caps.
